CLAIM

We claim the ornamental design for a test box as shown and described.

DESCRIPTION

FIG. 1 is a perspective view of a test box showing our new design.

FIG. 2 is a front elevational view of the test box.

FIG. 3 is a rear elevational view of the test box.

FIG. 4 is a right side elevational view of the test box.

FIG. 5 is a left side elevational view of the test box.

FIG. 6 is a top plan view of the test box.

FIG. 7 is a bottom plan view of the test box.

FIG. 8 is a perspective view of the test box with the front door and the rear door each in an alternate position.

The broken lines in the drawings define boundary lines and form no part of the claimed design.
